SHEET REGISTERING AND FEEDING
MECHANISM

William F. Huck, Richmond Hill, N. Y., assignor,
by mesne assignments, to R. Hoe & Co., Inc.,
New York, N. Y., a corporation of New York

Application April 25, 1934, Serial No. 722,304

21 Claims. (Cl. 101—158)

This invention relates to printing machines, especially machines adapted to print from intaglio plates in which the printing plate is secured to a bed that is moved back and forth under an inking mechanism and an impression member, whereby the plate is inked and the design then imprinted on a sheet, and more particularly relates to an improved mechanism for use in feeding blank sheets between the inked plate and the impression roller.

The principal object of the invention is to provide an arrangement whereby sheets of paper may be manually placed and clamped in a predetermined order on a movable sheet supporting member and automatically moved to advance one edge of the sheet between an impression roller and printing plate so that the advancement of the sheet may be continued by the impinging action of the roller upon the sheet to effect a printing operation.

It is a further object to provide means to advance the sheet supporting member in unison with the forward movement of the printing plate and to automatically release the sheet supporting member after the sheet is engaged by the impression roller.

It is a further object to quickly return said sheet supporting member to the sheet loading position to allow an operator sufficient time for reloading before the return of the inked plate.

A still further object is to provide means to prevent the sheet supporting plate from being advanced until the sheet is properly arranged in its predetermined registered position.

It is also an object of the invention to provide a sheet supporting and feeding device of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

In general, a printing machine for which the invention is especially adapted, comprises a bed having a printing plate mounted thereon which is reciprocated forward and rearward under an impression roll, inking member and ink wiper in such manner that the printing plate will first be inked and wiped on the rearward motion of same, then will pass beneath the impression roller in spaced relation thereto to its rearmost position. When moving forward, the printing plate will

receive a sheet and will move beneath and in engagement with the impression roll to effect printing operation.

The device according to this invention, which cooperates with the reciprocable printing plate, comprises a means whereby a sheet may be manually set and clamped in an exact position on an intermittently movable plate while said plate is in an idle position. After properly clamping said sheet, the movable plate is adapted to be engaged by the reciprocable bed upon which the printing plate is mounted, and is then carried forward until the end of the sheet engages the impression roller, whereupon the movable plate is automatically released to be returned to its normal sheet loading position.

The preferred embodiment of the invention is illustrated in the accompanying drawings, wherein:

Figure 1 is a side elevational view of the sheet feeding mechanism, with parts broken away, showing the sheet close to its delivery position and gripper and latching mechanism in a position corresponding therewith;

Figure 2 is a view similar to Figure 1 on a reduced scale and showing the position of the latch mechanism after engaging a stop member;

Figure 3 is an enlarged view of the latch mechanism in the same position as that of Figure 2;

Figure 4 is a plan view of the sheet feeding mechanism with the parts in agreement with the position shown in Figure 2;

Figure 5 is an elevational view similar to Figure 2 but showing the sheet feeding mechanism returned to its normal starting position;

Figure 6 is a vertical section taken on the line 6 of Figure 3; and

Figure 7 is a fragmentary detail section taken on the line 7 of Figure 1.

A printing plate 11 is secured to a reciprocating bed 12, which bed is adapted to move the printing plate and a blank sheet 13 thereon into engagement with the surface of an impression roller 14, during its movement in a forward direction, and in spaced relation to said impression roller on the return movement thereof. The drive for said bed is not shown.

A mechanism is provided to automatically feed the blank sheets 13 to the inked printing plate as said plate moves forward toward the impression roller, which mechanism comprises a movable plate 15 slidably mounted on bars 16, said bars being supported by suitable brackets 17 secured to the machine frame 18. The means for supporting the movable plate 15 upon the bars 16

comprises slide blocks 19, which are fixed to said plate 15, and have openings 21 therein, through which the bars 16 pass. Coil springs 22 are extended between lugs 20 projecting below the movable plate 15 and the outer brackets 17 and are adapted to normally retain the said plate in a rearward or loading position as shown in Figure 5. When in said latter position, a pair of pistons 23, fixed to the outer brackets 17, project into chambers 24 for a purpose to be hereinafter explained.

The forward end of said movable plate 15 is of a rack formation with a number of equally spaced teeth 25 bent angularly downward, and 15 slightly to the rear thereof are gripper fingers 26, which are mounted on a shaft 27, and said shaft is rotatably mounted in end bearings 28 secured to the said plate 15. Two side stops 29 are secured to the movable plate 15 by means 20 of screws 31 and are laterally adjustable thereon.

A manually operated gripper set and automatic release mechanism is also carried by the movable plate 15 and arranged in duplicate along each side of said plate. Referring to the mechanism 25 of one side only, the same comprises a hand lever 32 having a hub member 32' fixed to a rocker shaft 33, which shaft is rotatably mounted in bearings 34—34 secured to and projecting below the movable plate 15. A link 35, positioned 30 above the plate 15, is connected at one end to the hand lever 32, which projects upward through an opening 36 in said plate, and to a lever 37 secured to the gripper finger shaft 27. Forming a part of the hand lever member 32', is a rearwardly extending arm 38 which has a roller 39 mounted at the end thereof, and a downwardly projecting portion has a lug 41 bent outward therefrom. A detent plunger 42 is slidably mounted within a bore 43 in a housing 44, and 40 is maintained in yieldable engagement with the roller 39 through the pressure of a spring 44' positioned within the bore.

Adjacent said hand lever member 32' is a latch lever 45, which is freely mounted on the rocker 45 shaft 33 and is joined to the hand lever arm 38 by means of a pin 46, in the arm 38, which projects into an elongated slot 47 in the latch lever. A shoulder lug 40 is provided on the upper portion 50 of the latch lever to stop the movement of same in one direction.

Directly beneath the movable plate 15 is a stationary plate 48 which has two side wings 49 supported on blocks 50 on the machine frame 18 and its rear end is supported on the rear bracket 17, as shown in Figure 4. The forward end of said plate 48 is fluted, as shown at 51, and is arranged so that the spaces between said flutes are in alignment with the rack teeth 25.

The bed 12, with its printing plate thereon, 60 slides forward and backward along the plane shown in the drawings and said bed has a hook 52 secured at each side of the rear end thereof, which hooks are adapted to engage the latch levers 45—45 located at each side of the movable plate 15. The inner end of each hook 52 is beveled at 53 and is adapted to engage the end of a latch lever 45 and the outer end of each hook is beveled as shown at 54. Stop pins 55—55 are secured within the ends of the blocks 50—50, and 65 are positioned in the path of the lugs 41—41 on the hand lever member 32'.

A plurality of end stops 56 are provided which 70 cooperate with the side stops 29 when registering a sheet on the movable plate 15, and are 75 secured to a transverse shaft 57 supported in

bearings 58, which bearings are mounted at each side of the machine frame. Each of said end stops 56 is provided with a toe 59 which will engage the upper surface of the stationary plate 48 upon the fluted portion thereof exposed between 5 the teeth 25, when the movable plate 15 is in the sheet loading position shown in Figure 5. While 10 in said position, a sheet 13 is placed on the movable plate, with one end extended beyond same, and is properly centered thereon by its engagement with the end stops 56 and side stops 29. A rocker arm 61 is secured at the end of the shaft 57, and is adapted to be rocked periodically through a link and lever arrangement indicated generally by the reference character 62 which are 15 actuated by one of the machine movements (not shown) in such manner as to lower the stops 56 when the movable plate 15 is returned to the stationary position shown in Figure 5, and to raise 20 said stops before the movable plate is moved forward again.

The operation of the device will now be described:

When the movable plate 15 is in an idle or sheet loading position, shown in Figure 5, an operator 25 will place a sheet 13 upon the surface of said movable plate and center same by moving the front edge into engagement with the toes 59 of the end stops 56, while the sides of the sheet will engage the side stops 29. The sheet is then 30 clamped in its registered position by means of the hand lever 32, which is moved rearward from the position shown in Figure 2 to the position shown in Figure 5, and during its movement, will cause the gripper fingers 26 to be lowered to engage the sheet through the link and lever connection 35 and 37. Also when said hand lever 32 is moved to clamp the sheet, the latch lever 45 moves downward therewith.

During the period in which the blank sheet is 40 being set up for a printing operation, the bed 12 with the printing plate 11 thereon is normally traveling across the machine to print and discharge the sheet and then returns to a starting position. Before the bed 12 reaches the end of its 45 rearward movement, the cam portion 54, at the end of each hook 52, will rock the loosely mounted latch levers 45 upwardly around the shaft 33, after which they will drop in front of the beveled inner ends 53 of the hooks. The downward movement of the latch levers is limited by the engagement of the shoulder lugs 40 thereon with the under surface of the movable plate 15. Also during the period that the printing plate 50 is moved beyond the impression roll, the mechanism for controlling the end stops 56 functions to bring the stops into engagement with the movable plate 15, after said plate returns to a sheet loading position, and before the movable plate is again moved forward the end stops are 60 lifted.

Having reached the end of its rearward movement, the bed 12 will again start its forward movement, and as it moves, the latch lever 45 at each side of the movable plate will be engaged by the beveled portions 53 of the hooks 52. This condition will force the shoulder lugs 40 of said latch levers backward against the under side of the movable plate, and will cause the said plate to be drawn along with the bed. The 70 forward end of the blank sheet 13 will now slide from the surface of the stationary plate 48 onto the surface of the printing plate, and will be moved forward with the bed in the relation shown in Figure 1, until the lugs 41, at the lower end 75

of the hand lever arms 38, strike the stop pins 55. Upon the engagement of said lugs with the stop pins, the hand levers will be thrown forward in a manner indicated in Figure 3, and the gripper fingers will be released from their clamped engagement with the blank sheet just as the said sheet is impinged between the impression roller and the printing plate.

When the hand levers are thrown forward, the pins 46 thereon will strike the upper walls of the slots 47 and will thereby withdraw the latch levers from their engagement with the hooks 52, whereupon the movable plate will be released from its driving relation with the moving bed 12, and will be abruptly returned by the springs 22. The shock caused by the abrupt return of said movable plate is absorbed by the action of the piston and chamber members 23 and 24, as the chamber portions slide over pistons and produce a cushioning effect. After said movable plate is returned to its rest position, it is again ready to have a new sheet placed and clamped thereon.

If a condition should occur whereby time would not permit a new blank sheet to be clamped on the movable plate before the return of the bed 12, the hook 52 on said bed would pass clear of the latch lever 45, due to the latter being in a raised position, and the printing plate would 30 pass through one cycle of operation without printing a sheet.

It will be understood that the invention may be embodied in other specific forms without departing from the spirit or essential attributes 35 thereof, and it is therefore desired that the present embodiment be considered in all respects as illustrative and not restrictive, reference being had to the claims rather than to the foregoing description to indicate the scope of the invention.

What I claim is:

1. In a sheet feeding mechanism operable upon a printing plate, a sheet supporting member normally maintained in a sheet loading position, means to move said sheet supporting member to a printing position, and means to retract same to its loading position while the printing operation is in progress.

2. In a sheet feeding mechanism operable with a printing plate supported upon a reciprocating bed, a sheet supporting member adapted to receive a sheet while in a stationary position, means to join said sheet supporting member with the reciprocating bed to move the sheet to a printing position, and means to release said sheet supporting member from said reciprocating bed upon reaching said printing position.

3. In a sheet feeding mechanism operable with a printing plate supported upon a reciprocating bed, a sheet supporting member normally maintained in a sheet loading position, a connecting member adapted to maintain said sheet supporting member in joined relation with the reciprocating bed to move same therewith to a printing position, means to release said connecting member after reaching said printing position, and retracting means to return said sheet supporting member to a sheet loading position while the printing operation is in progress.

4. In a sheet feeding mechanism operable with a printing plate supported upon a reciprocating bed, a movable sheet supporting plate normally maintained in a sheet loading position, a clamping member to clamp the sheet in a registered position, means engageable with the reciprocating

bed to move said sheet supporting plate therewith, a stop member to limit the movement of the sheet supporting plate and to release said clamp, and means to retract said sheet supporting plate.

5. In a sheet feeding mechanism operable with a printing plate supported upon a reciprocating bed, a movable sheet supporting plate normally maintained in a sheet loading position, a clamping member to clamp the sheet in a registered position, a latch on said sheet supporting plate, and means on said reciprocating bed engageable therewith to move said sheet supporting plate on the forward stroke thereof, a stop to release said latch after reaching a printing position, and means to return said sheet supporting plate to its loading position.

6. In a sheet feeding mechanism operable with a printing plate supported upon a reciprocating bed, a movable sheet supporting plate normally maintained in a sheet loading position, a stationary plate below said sheet supporting plate, a movable end stop engaging said stationary plate to limit the end position of a sheet, a clamping member to clamp the sheet in a set position, and means for removing the end stops from the end of the sheet after the same is clamped, means to move the sheet supporting plate with the reciprocating bed to a printing position, and means for retracting said movable plate after the sheet is in said printing position.

7. In a sheet feeding mechanism operable with a printing plate supported upon a reciprocating bed, a movable sheet supporting plate normally maintained in a sheet loading position, sheet registering members and a clamping member to clamp the sheet in a registered position, a latch on said sheet supporting plate and a hook on the reciprocating bed engageable therewith to move the sheet supporting plate to a printing position, means to release said latch from engagement with the hook and release said clamping member upon reaching a printing position, and means for returning the sheet supporting plate to its loading position.

8. In a sheet feeding mechanism operable with a printing plate supported on a reciprocating bed, a movable sheet supporting plate normally maintained in a sheet loading position, sheet registering members and a clamping member to clamp the sheet in a registered position, a latch on said sheet supporting plate and a hook on the reciprocating bed engageable therewith to move the sheet supporting plate to a printing position, a manually actuated lever to move said clamping member to a clamping position and to move said latch into the path of the hook, and means engageable with an abutment to move said manually actuated lever to a clamp and latch releasing position.

9. In a sheet feeding mechanism operable with a printing plate supported on a reciprocating bed, a movable sheet supporting plate normally maintained in a sheet loading position, sheet registering members, clamping members to clamp the sheet in a registered position, a latch on said sheet supporting plate and a hook on the reciprocating bed engageable therewith to move the sheet supporting plate to a printing position, a manually actuated lever connected with said clamping member and latch to simultaneously move said clamping member to a clamping position and to move said latch into the path of the hook, and an abutment projecting into the path

of a portion of said hand lever to simultaneously release said clamp and latch members.

10. In a mechanism for feeding a sheet between an impression roller and a reciprocating printing plate, a movable sheet supporting plate adapted to have a sheet deposited thereon, means to move said sheet supporting plate forward until the sheet is impinged between the impression roll and the printing plate, means to release said movable plate directly upon the impingement of the sheet, and means to return said movable plate to a sheet loading position to permit the deposit of another sheet thereon while the printing of the previous sheet is in progress.

15. 11. In a mechanism for feeding a sheet between an impression roller and a reciprocating printing plate, a movable sheet supporting plate normally maintained in a sheet loading position, registering stops to guide a sheet in position on said plate 20 with one end of said sheet overhanging the edge thereof, means to move said sheet supporting plate forward with the printing plate until the overhanging end of the sheet is impinged between the impression roll and printing plate, and means 25 to release said movable plate for the return thereof.

12. In a mechanism for feeding a sheet between an impression roller and a reciprocating printing plate, a movable sheet supporting plate normally maintained in sheet loading position, a stationary plate positioned beneath said sheet supporting plate, intermittently moving end stops engaging said stationary plate ahead of the sheet supporting plate to permit one end of a sheet to overhang 30 said supporting plate, means to move said sheet supporting plate in unison with the printing plate and with the overhanging edge of the sheet engaging said printing plate, and means for releasing said sheet supporting plate when the sheet 35 engages the impression roll.

13. In a mechanism for feeding a sheet between an impression roller and a reciprocating printing plate, a movable sheet supporting plate normally maintained in a sheet loading position, registering 40 stops to control the position of the sheet on said plate and permitting one end to extend over the edge thereof, clamping members to clamp said sheets, means to move the sheet supporting member forward with the printing plate and with the extended end of the sheet engaging the printing plate, and means to release said clamp and sheet 45 supporting plate when the extended end of the sheet is engaged by the impression roll.

14. In a sheet feeding mechanism operable with 50 a printing plate supported upon a reciprocating bed, a slidable sheet supporting plate, guide rails to support said sheet supporting plate, sheet registering stops, gripper fingers to clamp a sheet in a registered position, latch members carried by 55 the sheet supporting plate and hooks on the reciprocating bed adapted to engage said latch members, a manual control member to control the position of the gripper fingers and latch members, and means to automatically actuate said 60 manual control member.

15. In a sheet feeding mechanism operable with 65 a printing plate supported on a reciprocating bed, an impression roller cooperating with said printing plate, a sheet supporting member adapted to have a sheet placed thereon, means to move said sheet supporting member with the reciprocating bed to advance the sheet until the leading edge thereof is impinged between the printing plate and the impression roller, and means to return 70 said sheet supporting member after reaching said

latter position to permit reloading before the printing plate is in position to receive another sheet.

16. In a sheet feeding mechanism operable with a printing plate supported on a reciprocating bed, an impression roller cooperating with said printing plate, a movable sheet supporting member, means to register a sheet on said sheet supporting member with the leading edge of the sheet overhanging the leading end of the sheet supporting member, means to move said sheet supporting member forward until the leading end of the sheet is engaged by the impression roller to thereby continue the feed of the sheet, and means to return said sheet supporting member after the sheet is engaged by the impression roller.

17. In a sheet feeding mechanism operable with a printing plate supported on a reciprocating bed, an impression roller cooperating with said printing plate, a movable sheet supporting member, means to register a sheet on said sheet supporting member, means to clamp a sheet in the registered position, means to move said sheet supporting member forward until the leading end of the sheet is engaged by the impression roller to thereby continue the feed of the sheet, means to release the sheet clamping means upon the engagement of the sheet with the impression roller, and means to return said sheet supporting member to a loading position while the printing operation of the previous sheet is in progress.

18. In a mechanism for feeding a sheet to be printed upon, a sheet supporting member adapted to receive and hold a sheet thereon with an edge thereof extending beyond an edge of said member, means to move said member with the supported sheet to present the extended edge of the sheet at the point of engagement of an impression cylinder in association with a reciprocating printing plate, and means operable when the extended sheet edge is gripped between the cylinder and the printing plate to return said sheet supporting member to its initial position to receive a sheet.

19. In a sheet folding mechanism operable with an impression cylinder and a printing plate, a sheet supporting member to carry the sheet to a printing position to be engaged by and between the impression cylinder and the printing plate, means to move said sheet supporting member toward said cylinder, and means to retract said sheet supporting member to dispose the supported sheet upon the printing plate.

20. In combination with a cylinder of a printing machine and a reciprocating plate cooperating with said cylinder to act upon a sheet, a sheet supporting member, means to move said member with said plate to carry a sheet toward said cooperating cylinder and plate, and means to retract said sheet supporting member to dispose the sheet upon said plate and return the member to its initial position for another sheet.

21. In a printing machine, the combination of cooperating members operable to grip and draw a sheet therebetween, a sheet receiving and supporting member, means to move said member to carry a supported sheet to the cooperating members, and means to retract said sheet supporting member, when the same has carried the supported sheet to the cooperating members and is gripped thereby, and means to return it to its initial sheet receiving position while the sheet is being drawn between said members by the cooperating action thereof.
